UNITED STATES PATENT OFFICE.

PERCY E. HEATHERBELL, OF DEEP BAY, AND GORDON G. HEATHERBELL, OF PORT CYGNET, TASMANIA, AUSTRALIA.

AIR-INDUCTION APPARATUS.

1,323,981.

Specification of Letters Patent.

Patented Dec. 2, 1919.

Application filed January 26, 1915, Serial No. 4,525. Renewed July 7, 1919. Serial No. 309,182.

To all whom it may concern:

Be it known that we, **PERCY E. HEATHERBELL** and **GORDON G. HEATHERBELL**, both subjects of the King of Great Britain, residing at Deep Bay and Port Cygnet, in the State of Tasmania and Commonwealth of Australia, have invented certain new and useful Improvements in Air-Induction Apparatus, of which the following is a specification.

Our invention relates to impelling apparatus for ducts and is principally designed for use in chimneys or stacks leading from stoves and furnaces, for operation to induce and increase the draft for the fires within the stoves and furnaces.

With the foregoing end in view, the invention relates to a novel construction, arrangement and combination of durable parts designed to effectively accomplish the function stated and for manufacture at low cost.

Definite objects with respect to auxiliary functions are to provide apparatus of this nature having one or more blades, preferably pivoted off center, which will normally seek the vertical so as not to obstruct the draft while at rest; effective means forming an abutment to prevent rotation of the blades by impingement of the air against them and manually operable means to positively drive said means.

Additional objects will hereinafter appear from the description following taken in connection with accompanying drawings wherein in the preferred embodiment is illustrated.

In said drawings:

Figure 1 is a view showing our improved apparatus in elevation and in connection with a stove pipe, the latter being partly in elevation and partly in section;

Fig. 2 is a cross sectional view on the line 2-2 of Fig. 1;

Fig. 3 is a perspective view of the blade supporting bracket, and

Fig. 4 is a detail sectional view on the line 4-4 of Fig. 1.

Referring specifically to the drawings wherein like reference characters designate like or similar parts, a duct is shown at 1 which is a stove pipe section of thin metal and round in cross section. Internally of the duct 1 are mounted suitable bearing bars 2 which at their ends have angle lugs 3 through which pass removable fastening bolts 4, and which bolts removably pass

through the wall of duct 1, to secure the bearing bars in place. Journaled in the bearing bars 2 is a longitudinally extending shaft 5 which has a square portion 6. A suitable bracket 7 is fastened to the shaft 5. 60 This bracket comprises a collar 8 and opposed arms 11 terminating in oblique abutments 12 forming stops. The collar 8 has a square opening 9 to receive a square portion 6 of the shaft 5, a screw 10 threaded in 65 a side of the collar serving to secure the bracket to the shaft. The abutments or stops 12 incline laterally in opposite directions and limit the movements of the blades 13 in one direction. Blades 13 are pivotally 70 mounted on the arms 11 by means of cleats 14, off center, so that the greatest area of the blades longitudinally of shaft 5 will be above the arms 11. To the blades 13 are suitably fastened at proper desired locations, 75 weights 14' which serve to normally maintain the blades in a vertical position and to cause the blades to seek a vertical position after an operation. Specifically these weights are shown as fastened at the lower 80 edge of the blades and on the sides thereof to which the arms 11 are fastened.

A bevel gear wheel 15 is keyed or otherwise fastened to the shaft 5 below the lowermost bearing bar 2. Meshing with the bevel gear wheel 15, is a bevel gear wheel 16, preferably of greater diameter, which is mounted on a shaft 17 having a crank 18 at one end on which is turnably mounted a handle 19 of wood, metal or other desired material. The 90 opposite end of shaft 17 is bent or deflected at an angle to the remainder of the shaft at 20 in order to fasten the shaft to the duct 1.

In use, handle 19 is manually engaged and turned, thereby turning the operating 95 shaft 17 which through the medium of gears 15 and 16 rotate the shaft 5. Shaft 5 through the medium of the bracket 7 rotates or turns the blades 13 in a horizontal plane. The action of the blades induces air into 100 the duct or pipe 1 thereby increasing the draft, in the stove, furnace or the equivalent, from which the duct or pipe, leads. As previously stated, the weights 14' maintain the blades 13 in a vertical position while at 105 rest. However when shaft 5 turns, by the impingement of the air against the blades or plates, they contact with the abutments 12 which serve to support them in angular positions, and at different angles to each 110

other. Due to the fact that the greatest area of the blades is above the axis of the arms 11, the impingement of the atmosphere can turn the blades against the abutments 12. This overcomes the liability of the blades overturning or being turned in the counter direction by the atmosphere during horizontal rotation, as less air-impinging surface is provided below than above the axis of the arms 11.

While our improvements relate particularly to a means to increase the draft in ducts or pipes leading from stoves and furnaces, it is nevertheless capable of use for other purposes, for instance, stirring and mixing various materials, and as a fan, and hence limitation to a special use is not to be inferred. Also changes in the details of construction, combination and arrangement of the parts may be resorted to without departing from the spirit and scope of the invention.

Having thus described our invention, what we claim is:—

- 25 1. In apparatus of the character specified, a duct, a shaft journaled longitudinally of the duct, a bracket rotatable with the shaft and comprising arms extending outwardly from the shaft and across the duct and provided with stop extensions, blades pivotally mounted on the arms and present-

ing unequal surfaces on opposite sides of their respective axes and limited in their pivotal movements in one direction by the said stop extensions and normally occupying a vertical position, and means for imparting a rotary movement to the said shaft.

2. In combination, a vertical duct, supporting members secured within the duct, the one above the other, a centrally disposed shaft journaled in the supporting members, a bracket secured to the shaft and having opposed arms provided at their outer ends with oblique extensions forming abutments, blades pivotally mounted upon the arms and weighted at their lower edges to normally hold the blades in vertical position, the blades presenting a greater area above their supporting arms and limited in their pivotal movements in one direction by the said abutments, and a horizontal shaft mounted in the duct and geared to the centrally disposed shaft and adapted to have power applied to a projecting end thereof.

In testimony whereof we affix our signatures in presence of two witnesses.

PERCY E. HEATHERBELL.
GORDON G. HEATHERBELL.
